[57] CLAIM

The ornamental design for a hook for hanging tubular objects, as shown and described.

DESCRIPTION

FIG. 1 is a rear, top and left side perspective view of a hook for hanging tubular objects showing our new design;

FIG. 2 is a left side elevational view thereof;

FIG. 3 is a top plan view thereof;

FIGS. 4 and 5 are respectively front and rear elevational views thereof; and,

FIG. 6 is a bottom plan view thereof.

FIG. 1.

FIG. 3.

FIG. 4.

FIG. 2.

FIG. 6.

FIG. 5.
